UNITED STATES PATENT OFFICE.

AAGE INGEMANN ERIKSEN, OF HOLSTEBRO, DENMARK.

PHOTOGRAPHIC CAMERA.

Application filed March 31, 1926. Serial No. 98,891.

This invention relates to a photographic roll film camera and consists in the provision of means for holding in said camera a plurality of film rolls as well as means for unwinding such films separately for exposure.

The invention is illustrated in the accompanying drawings which show the preferred form of construction.

Fig. 1 represents a sectional front view 10 of the camera.

Fig. 2, a section on the line II—II of Fig. 1, and

Fig. 3, a cross-section on the line III—III of Fig. 2.

Fig. 4 is a perspective view of a detail.

The camera casing 1 has at one end a film carrier composed of a shaft 2 and two discs 7 and 8 which are fixed to said shaft. One end of the shaft projects through the camera 20 casing and is fitted with a thumb-piece 3 whereby the shaft can be turned. A disc 4 which turns with the shaft, is fitted with a plurality of equidistant apertures for the reception of a pin 6 carried by a spring 5.

25 The latter is secured at one end to the casing 1 and serves to lock the shaft in different positions of rotary adjustment. A plurality of films 40, applied together with their protective backing strips to spools 37 in the

30 usual manner, is mounted between the discs 7 and 8. To hold the film rolls in position the disc 7 is provided with axially adjustable pivot pins 9 which are controlled by springs 10, and the disc 8 is fitted with 35 small shafts 11 which can be rotated in opposition to springs 12. The film rolls are held between the pins 9 and the shafts 11 both of which project through the discs 7 and 8. One end plate 39 of the spool 37

40 has a round recess for the reception of the pivot pin 9, and the other end plate 38 has a square recess for the reception of the square end 13 of the shaft 11 which latter, therefore, becomes coupled to the spool. The

45 arrangement is such that the film unwinds in opposition to the spring 12. The film, or rather its protecting strip, carries at its outer end a thin rod 42 which extends beyond the edges of the strip and for the 50 reception of which the discs 7 and 8 are formed with notches 14 and 15 respectively. The apertures in the disc 4 correspond to the film arrangement in the carrier so that the latter can be secured with any of the films 55 in position for use. The end plates of the

spools may be formed with notches 45 (Fig. 2) for the reception of the rod 42 when the films are packed away.

At the opposite end of the casing 1 a take-up roller 30 is arranged. The latter is 60 composed of a hollow cylinder which is provided with a longitudinal slot 31' extending to the center of the end plates 29. The roller is embraced by guide plates 31 within which it can be rotated, these plates 65 being connected to the casing 1. Springs 32 normally engage notches 32' in the end plates 29 of the roller so as to hold the latter normally with the slot facing upwards. Normally supported in the slot of the roller 70 is a shaft 22 which carries two discs 23 and 24 arranged so as to cover the end plates 29 of the roller 30. Each of these discs is fitted on its inner side with two spaced projections 27 and 28 which normally extend into the slot of the roller 30. The shaft 22 and its discs can be lifted off the roller 30 for which purpose a U-shaped frame 19 is provided. The latter moves between two parallel walls 16 and 16' on the casing 1. It 75 has a centrally disposed handle 18 which projects from the casing through a slot 17 in the wall 16. The end members 20 and 21 of the frame move in laterally disposed slots 15' in the wall 16' and are in rotatable engagement, one with the projecting end of the shaft 22 the other with a boss 25 formed centrally on the disc 23. A spring 26 on the member 20 engages a notch in the disc 23 and holds the discs 23 and 24 normally with 80 the projections 27 and 28 in the uppermost position. The boss 25 has a female screw-thread for the reception of a high-pitched screw 34. The latter is slidably guided in a sleeve 33 on the casing 1 and is normally held by a spring 36 out of contact with the boss 25. The screw has a milled head 35 whereby it can be pushed into engagement with its screw socket in the boss 25 and used 85 for turning the take-up roller.

100 The modus operandi is as follows:

Before an exposure, the pin 6 is released from the disc 4, and the film carrier is turned to a position which is intermediate between two of those in which it can be locked. Then the handle 18 is raised in its slot so as to lift the shaft 22 and its disc from the roller 30 and place the discs against the film carrier. The projections 27 and 28 of the 105 discs 23 and 24 will then be situated relative 110

to the path of the rods 42 so that, on the film carrier being restored to a locked position, the projections will receive the ends of the rod of one of the films between them. If now the frame 19 is restored to its initial position, the rod 42 will be carried along by the projections 27, and the film will be unwound in opposition to the spring 12. The rod enters the slot in the roller 30 together with the projections, and the roller can then be used for further unwinding of the film. This is effected by means of the screw 34 which is pushed into engagement with the boss 25 and turned in the direction of the screw-thread. Ledges 43 support the film and hold it in the focal plane. If the film is long enough to receive more than one picture, suitable known means are provided for indicating the amount of unwinding for each picture. The springs 32 and 26 tend, by engagement with their notches, to retain the roller 30 against the pull of the spring 12. When the film has been exposed, the roller 30 is turned in the opposite direction, and the film is once more wound on to its spool under the influence of the spring 12. The film being unwound from the roller 30 it resists further movement of the screw in this direction, and the screw then leaves the boss 25 and sets the shaft 22 free. Then the latter can be raised by means of the frame 19 so as to allow the film and its protecting strip to re-wind completely on to the spool, whereupon the carrier is turned so as to place another film in position for use.

Exposed films can be removed from the carrier for development whenever required, and new films can be inserted.

Depending on the size of the discs 7 and 8 and of the film rolls, any number of films may be accommodated in the carrier in this manner.

The construction of the device may be varied without departing from the spirit of the invention.

I claim:

1. In a photographic roll film camera, a casing, a rotatable film carrier arranged at one end of said casing, means on said carrier for holding a plurality of film rolls, a take-up roller arranged at the opposite end of the casing, and means operated from the outside of the casing for carrying the end of each separate film across the casing and connecting it to the take-up roller.

2. In a photographic roll film camera, a casing, a film carrier at one end of said casing comprising a rotatable shaft, discs carried by said shaft, resilient pivot elements spaced around said discs for holding a plurality of film rolls between the latter parallel with the shaft, a take-up roller at the opposite end of the casing, and means operated from the outside of the casing for carrying the end of each separate film across the cas-

ing and connecting it to the take-up roller.

3. A structure as claimed in claim 2 wherein one set of pivot elements are coupled to the film rolls so as to participate in their rotation, and springs connected to said latter pivot elements so as to oppose the unwinding of the films and cause their re-winding when released. 70

4. In a photographic roll film camera, a casing, a rotatable film carrier at one end of said casing, means for attaching a plurality of film rolls to said carrier so that each film can be brought into position for use by an adjustment of the carrier, springs controlling the film rolls so as to oppose their unwinding and effect a re-winding of the same when released, rods connected to the ends of the films, a take-up roller at the opposite end of the casing, and means for carrying the rods and the film ends separately across the casing and connecting them to the take-up roller. 75

5. In a structure as claimed in claim 4, a take-up roller comprising a cylinder supported rotatably in the casing, a shaft accommodated normally in a longitudinal slot in said cylinder, means operated from the outside of the casing for moving the shaft through the space between the take-up roller and the film carrier, means for connecting the shaft to the rod at the end of the film so that the latter can be drawn together with the shaft into the slot in the take-up roller, and means for rotating the latter so as to unwind the film. 80

6. In a structure as claimed in claim 4, a take-up roller comprising a cylinder supported rotatably in the casing, a shaft accommodated normally in a longitudinal slot in said cylinder, means operated from the outside of the casing for moving the shaft through the space between the take-up roller and the film carrier, discs connected to said shaft, means on said discs for connecting the latter to the rod at the end of a film so that the latter will be drawn together with the shaft into the slot of the take-up roller, and means for rotating the latter so as to unwind the film. 85

7. In a structure as claimed in claim 4, a take-up roller comprising a cylinder supported rotatably in the casing, a shaft accommodated normally in a longitudinal slot in said cylinder, a frame holding said shaft, said frame being guided in slots in the casing so that it can be used for moving the shaft through the space between the take-up roller and the film carrier, discs connected to said shaft, means on said discs for connecting them to the rod at the end of a film and drawing said rod into the slot in the take-up roller, and means for rotating the latter so as to unwind the film. 90

8. In a structure as claimed in claim 4, a take-up roller comprising a cylinder sup- 125

ported rotatably in the casing, a shaft accommodated normally in a longitudinal slot in said cylinder, a frame holding said shaft, said frame being guided in slots in the casing so that it can be used for moving the shaft through the space between the take-up roller and the film carrier, discs connected to said shaft, projections on said discs adapted to engage the rod at the end of a film and pull it together with the shaft into the slot in the take-up roller, and means for rotating the latter so as to unwind the film.

9. In a photographic roll film camera, a casing, a rotatable film carrier at one end of said casing, means for attaching a plurality of film rolls to said carrier so that they can be turned by the latter separately into position for use, springs opposing the unwinding of the films and tending to rewind them on release, a take-up roller held rotatably at the opposite end of the casing, a shaft accommodated normally in a longitudinal slot in said take-up roller, a frame holding said shaft, said shaft being guided

in slots in the casing so that it can be used for moving the shaft through the space between the take-up roller and the film carrier, a rod connected to the end of each film, means for causing said rod to be engaged to the shaft so that it can be drawn by the latter into the slot in the take-up roller, a screw fitted in the casing so that it can be temporarily connected to the shaft when the latter is located in the take-up roller, and means for coupling the shaft to the roller so that the latter can be turned by means of the screw.

10. The structure claimed in claim 9 and ledges arranged in the casing so as to support the unwound film in position for exposure.

11. The structure claimed in claim 9 including an additional casing wall covering the frame and its guide slots, and an operating handle connected to the frame and projecting through a slot in said additional wall.
